UNITED STATES PATENT OFFICE

HERMANN SCHÜLER AND FRITZ HERLACH, OF DUSSELDORF, GERMANY, ASSIGNORS TO RHEINISCHE METALLWAAREN- UND MASCHINENFABRIK, OF DUSSELDORF-DERENDORF, GERMANY, A CORPORATION OF GERMANY

GUN MOUNTED ON A WHEEL CARRIAGE

Application filed August 16, 1929, Serial No. 386,450, and in Germany November 29, 1926.

Our invention relates to a gun mounted on a wheel carriage and having an intermediate carrier for the gun adapted to be swung into an upright position in order to change the firing height of the gun. The invention has for its object to so improve guns of this type which are capable both to long range and high angle fire, by mounting the gun barrel so as to be swung in all directions and set 10 very quickly, that they can be used to combat swiftly moving aims such as aircraft.

To this end according to our invention the gun barrel is mounted on the intermediate carrier so as to be swung about three crossing 15 or intersecting axes. These three axes for the gun barrel advantageously are so arranged on the intermediate carrier that in setting the gun barrel to low firing height for long range fire one of the three axes extends nearly or exactly horizontally in the 20 longitudinal direction of the carriage, whilst the two remaining axes are arranged like the normal training axis and trunnion axis of a gun, that means the former extends vertically 25 and the latter horizontally relatively to the carriage.

By throwing over the intermediate carrier to low firing height a normal long range gun of limited setting ability is thus obtained to the barrel of which the training 30 and elevating motion is imparted by swinging it about these two latter axes. The above third axis that extends in the longitudinal direction of the carriage can be used to eliminate lateral inclination of the axis of the 35 horizontal trunnions in the event the carriage wheels differ in level.

When aerial aims should be attacked the intermediate carrier is erected so far by 40 swinging it into an upright position on the carriage that the axis that formerly extended horizontally in the longitudinal direction of the carriage assumes a vertical or approximately vertical position whereby an unlimited setting possibility of the gun barrel in 45 the space is obtained. The elevation is thereupon imparted to the gun barrel advantageously in the same manner as with low firing height by swinging it about the trunnion axis, while the lateral train can be im-

parted to it selectively by turning it about the one or other of the two remaining setting axes.

In order that our invention can be more easily understood an embodiment of our improved gun is illustrated by way of example 55 in the accompanying drawing in which—

Figure 1 is a lateral view of a gun having a barrel adapted to freely swing about its setting axes and an intermediate carrier which is formed by a pedestal that can be thrown over on the carriage, the gun being 60 illustrated in firing position, with the pedestal down;

Figure 2 is a similar view with the pedestal in erected position; 65

Figure 3 is a top view of Figure 2, the gun barrel being removed, and

Figure 4 illustrates the gun in travelling position, the gun barrel being thrown over 70 to an inverted position with the muzzle down.

Referring to these drawings *a* denotes the wheeled carriage the trail of which terminates in *a* platform resting on the ground. This platform has mounted on it a pedestal *b* which can be thrown over in a vertical plane about a horizontal pin *c* and carries by a pivot pin *d* a pivot head *e* which can be turned freely 360 degrees. When the pedestal *b* assumes the down position illustrated 75 in Figure 1, the pivot head rests on the wheel axle *f* and is thereby prevented from turning about the pivot pin *d* which in this position extends horizontally in the longitudinal direction of the carriage. To prevent unintentional lifting of the pivot *e* it can be rigidly connected to the wheel axle by means 80 of any suitable coupling means (not shown). Furthermore, this arrangement may be so designed that also in the down position of 85 pedestal *b* the pivot head *e* is able to be swung about the pivot pin *d* so that the latter may be used to eliminate oblique position of the axis of the horizontal trunnions.

The pivot head *e* has mounted on it normally to pivot pin *d* and so as to be swung 360 degrees the pin *g* of a fork *h* that carries the bearings for the horizontal trunnions *i* of the cradle *k* in which the gun barrel *l* is 90 guided. 95

When swiftly moving aims more particularly aerial aims should be fired at, the pedestal *b* is lifted from the wheel axle *f* and rigidly connected in upright position to the carriage *a* by means of an inclined support *m*.
 5 In this position the pivot pin *d* stands approximately vertically, the pin *g* of the trunnion fork *h* assumes a nearly horizontal position and the gun barrel *l* owing to its being free to be swung about three setting axes can be set very easily and quickly to every point in the space, irrespective which of the three setting axes respond to turning motion in tracing the aim. In so doing advantageously those of the three axes are selected or will offer themselves as the best ones to warrant the most convenient and quick setting of the gun barrel to the desired position and the lowest resistances to be overwhelmed in the setting motion.
 10

The gun barrel *l* is set and fixed in set position by means of the handle *n*, but also two such handles may be arranged beside one another. The handle *n* is mounted on the cradle *k* so as to be turned about an axis *o* parallel to the axis of the trunnions *i*, so that in all positions of the gun barrel, even with great elevations, a position can be imparted to it that permits easy setting, see Figure 2.

The firing mechanism (not shown) is arranged on the cradle *k* so as to be turned like handle *n* and is so connected to the latter by suitable means that it follows its setting motions and always is in a proximity to handle *n* so as to be manipulated by the operator's hand that is grasping the handle. For instance the trigger may be mounted in the handle itself, as usual in fire arms the handle of which is rigid on the casing, and the connection to the firing hammer lodged in the closure of the gun barrel is established in this case preferably by means of a Bowden cable.

The possibility of turning the trunnion fork *h* 360 degrees about the pin *g* (a one side turn by 180 degrees would give the same effect) enables the gun barrel to be turned over to the rear so far into a travelling position that its muzzle comes to lie above the carriage, see Figure 4. In this manner the overall length of the gun is favorably reduced for transport.

When the gun barrel is swung about the pin *g* while the pedestal *b* is in erected position, a turning moment about the axis of pivot pin *d* arises in firing which moment increases with increasing lateral train about pin *g* and in training beyond 10 degrees becomes so great that it cannot long be taken up by the operator's hand. For this reason a coupling device is provided according to the invention which for instance consists in a spring-loaded locking lever and automatically firmly couples the pivot head *e* with the pedestal *b* when the gun barrel is trained

about the pin *g* about 10 degrees, so that the turning moment is transmitted by pedestal *b* to the carriage. The gun barrel then can be swung merely about the axes of pin *g* and trunnions *i*, that means, it can no longer be turned about pivot *d*. This latter possibility, however, is re-established when the gun barrel returns about pin *g* to an angle of less than 10 degrees.

For some fighting situations it will be suitable to not limit the possibility of turning the gun barrel about the axis of pivot *d*. In this case it is required to eliminate for both sides the motion beyond 10 degrees about the axis of pin *g*, this being made again by means of a locking device similar to that described above. Furthermore, these two locking devices can be combined on the gun in order to obtain the possibility of selectively setting the gun barrel in the one or other manner, and are then brought to a mutual relation such as to cause the one device to be thrown out when the other is selected, and inversely.

In the embodiment hereinbefore described the gun barrel is able to freely swing about its setting axes. As a matter of course, self-locking and eventually disengageable setting gears can be interposed between some or all of the mutually movable parts of the carriage and, further, an elevating gear can be provided between the pedestal *b* and the carriage *a*, to set different firing heights.

What we claim and desire to secure by Letters Patent is:—

1. A gun comprising a wheeled carriage, an intermediate member carrying the gun barrel and adapted to be turned on said carriage in a vertical plane into an upright and a low position, and means for turning the gun barrel on said intermediate member about three setting axes.

2. A gun comprising a wheeled carriage, an intermediate member carrying the gun barrel and adapted to be turned on said carriage in a vertical plane into an upright and a low position, and means for turning the gun barrel on said intermediate member about three setting axes, one of these axes extending at least approximately horizontally in the longitudinal direction of the carriage when said intermediate member is in low position, out of the remaining axes the one extending then horizontally and transversely of the carriage and the other vertically.

3. A gun comprising a wheeled carriage, an intermediate member carrying the gun barrel and adapted to be turned on said carriage in a vertical plane into an upright and a low position, and means for turning the gun barrel on said intermediate member about three setting axes, one of these axes extending at least approximately horizontally in the longitudinal direction of the carriage when said intermediate member is

in low position, out of the remaining axes the one extending then horizontally and transversely of the carriage and the other vertically, the turning amplitude of the gun barrel about said latter axis from the middle position amounting to at least 180 degrees.

4. A gun comprising a wheeled carriage, an intermediate member carrying the gun barrel and adapted to be turned on said carriage in a vertical plane into an upright and a low position, and means for turning the gun barrel on said intermediate member about three setting axes, one of these axes extending at least approximately horizontally 15 ly in the longitudinal direction of the carriage when said intermediate member is in low position, out of the remaining axes the one extending then horizontally and transversely of the carriage and the other vertical- 20 ly, manipulative means for turning the gun barrel about these axes, and disengageable means for automatically locking, with said intermediate member in upright position, the turning motion about said first-named lon- 25 gitudinally extending axis upon the gun barrel being turned beyond a determined amount about said vertical axis, and for re-establishing said turning motion upon the gun barrel returning to within said amount.

5. A gun comprising a wheeled carriage, an intermediate member carrying the gun barrel and adapted to be turned on said carriage in a vertical plane into an upright and a low position, and means for turning 35 the gun barrel on said intermediate member about three setting axes, one of these axes extending at least approximately horizontally in the longitudinal direction of the carriage when said intermediate member is in 40 low position, out of the remaining axes the one extending then horizontally and transversely of the carriage and the other vertical- 45 ly, manipulative means for turning the gun barrel about these axes, and disengageable means for admitting with said intermediate member in upright position a turning motion for the gun barrel about said vertical axis only by a limited amount.

6. A gun comprising a wheeled carriage, 50 an intermediate member carrying the gun barrel and adapted to be turned on said carriage in a vertical plane into an upright and a low position, means for turning the gun barrel on said intermediate member about 55 three setting axes one of them extending at least approximately horizontally in the longitudinal axis of the carriage when said intermediate member is in low position, out of 60 the remaining axes the one extending then horizontally and the other vertically, manipulative means for turning the gun barrel about these axes, disengageable means for automatically locking, with said intermediate 65 member in upright position, the turning mo-

tion about said first-named longitudinally extending axis upon the gun barrel being turned beyond a determined amount about said vertical axis, and for re-establishing said turning motion upon the gun barrel re- 70 turning to within said amount, and disen- gageable means for admitting with said in- termediate member in upright position a turning motion of the gun barrel about said vertical axis only by a limited amount, and 75 means for disengaging the one of said two disengageable means when the other is en- gaged and vice-versa.

In testimony whereof we have affixed our signatures.

HERMANN SCHULER.
